DESIGN FOR A FISHERMAN'S WADING BOOT

Ross Bartlett, Cortland, N. Y.

Application May 13, 1939, Serial No. 84,966

Term of patent 14 years

To all whom it may concern:

Be it known that I, Ross Bartlett, a citizen of the United States, residing at Cortland, in the county of Cortland, State of New York, have invented a new, original, and ornamental Design for a Fisherman's Wading Boot, of which the following is a specification, reference being had to the accompanying drawing, forming part thereof.

The figure is a perspective view of a fisherman's wading boot, showing my new design and in which the opposite side of said boot is plain.

I claim:

The ornamental design for a fisherman's wading boot, as shown and described.

ROSS BARTLETT.
